FUEL-INJECTION NOZZLE, ESPECIALLY FOR
LIGHT-OIL INJECTION MOTORSPaul Schüttler and Joseph Vollmer, Berlin-
Charlottenburg, Germany, assignors to Pallas
Apparate G. m. b. H., Berlin, GermanyApplication June 18, 1937, Serial No. 149,014
In Germany July 9, 1936

2 Claims. (Cl. 299—107.1)

In contradistinction to injection motors in which a heavy oil is used, the operation of light-oil injection-motors encounters additional difficulties due to the fact that the boiling point of light oils is considerably below the boiling point of heavy oils, in consequence whereof gas bubbles arise in the injection nozzle, which bubbles either impair the accurate supply of the small amount of fuel by the fuel pump or stop it completely.

10 The object of the present invention is to obviate the just-mentioned drawback, and for this purpose the transmission of heat from the motor body which is cooled by water or air to the injection nozzle is reduced to a minimum, in that 15 this nozzle is arranged outside the motor body and is in contact with it directly only at the place of injection, and indirectly only by certain outer holding means for said nozzle.

15 The invention is illustrated diagrammatically and by way of example on the accompanying drawing on which Figure 1 is a transverse vertical section through the portions concerned of a multiple light-oil injection motor designed according to this invention, and Figure 2 is an axial section through the left-hand half of Fig. 1.

20 In the drawing the reference numeral 1 identifies an injection nozzle for supplying light oil to the fuel passage 2 that extends through a water-cooled wall portion of the engine casing 3. The nozzle is held in place at the exterior of the engine casing by a clamp bolt 4 in a clamp arm 5 which is supported from the engine casing by studs 8. The cooperating contact surfaces at the inner end of the nozzle 1 and the exterior surface 25 of the engine casing at the fuel inlet 2 may be curved or flat, as desired, so long as a tight joint is formed. A gasket 6 of low heat conductivity may be arranged between the nozzle and the engine casing to reduce heat transfer at this point, and cooling fins 7 may be formed on the nozzle 1.

25 The nozzle is shielded from the intense heat

of the burning fuel by its location at the exterior of the engine casing, and the conduction of heat to the nozzle is limited to a low value by the limited contact areas between the casing 3 and the inner end of the nozzle, and between the 5 screw 4 and the outer end of the nozzle. The heat-insulating gasket 6 effects a further reduction in the heat transfer to the nozzle from the cooled engine wall 3. No difficulty has been experienced in operating with light fuel oil as 10 the described nozzle is not heated to temperatures that cause vaporization of the light fuel within the nozzle.

We claim:

1. In combination with an internal combustion engine of the type employing light oil as liquid fuel which comprises a casing having walls defining a cylinder and a recess adapted to receive a fuel injection nozzle, the wall at the base of the recess having a nozzle seat at its exterior 15 surface and a fuel passage extending through said wall from the nozzle seat to the interior of the cylinder, a fuel injection nozzle spaced from and communicating with said cylinder through said fuel passage, said nozzle having its body portion concentrically spaced from the walls of said recess and in contact with said engine casing at only two surfaces, namely, at the orifice tip which engages said nozzle seat through a restricted area 20 and at a clamping point at the outer end of the 25 nozzle, and a clamping means engaging said clamping point of the nozzle for maintaining the nozzle in position, whereby the conduction of heat from the engine casing to said nozzle is restricted to a minimum. 30

2. The invention as claimed in claim 1 wherein a gasket of low heat conductivity is arranged between the nozzle body and the nozzle seat of said engine casing. 35
